ACCELERATING PUMP

Filed Sept. 24, 1940

FIG. 1

INVENTOR
CHARLES E. MARKHAM

Donald U. Rice

ATTORNEY

UNITED STATES PATENT OFFICE

2,267,570

ACCELERATING PUMP

Charles E. Markham, St. Louis, Mo., assignor to
 Carter Carburetor Corporation, St. Louis, Mo.,
 a corporation of Delaware

Application September 24, 1940, Serial No. 358,049.

4 Claims. (Cl. 261—34)

This invention relates to carburetors for internal combustion engines and more particularly to accelerating devices used in connection therewith.

These devices usually comprise a plunger type pump which may be actuated by direct interconnection to the manually operated carburetor throttle valve or by suction in the carburetor conduit posterior to the throttle valve in a manner well known. The suction operated type has a distinct advantage over the throttle actuated type in that the accelerating discharge is automatically varied in accordance with the engine load.

Certain disadvantages are inherent, however, in the suction operated type. One of these disadvantages being that the pump will discharge when the engine is stopped due to loss of manifold vacuum. Means for locking the plunger in a loaded position, when the throttle is in a closed position has been proposed to overcome this difficulty. Another disadvantage, however, is the difficulty of building a pump of this type which will deliver the exact proportions of its total discharge as required. In other words, the spring discharge suction loaded type pump lacks the definite discharge control of the throttle interconnected type, a feature which is particularly essential in accurately controlling comparatively small discharges.

The present invention has for its primary object the provision of an accelerating device in which the advantages of both of the above mentioned types are incorporated and in which the disadvantages of these separate types are obviated.

Other objects and advantages will appear in the following description and accompanying drawing referring to which:

The figure is a somewhat diagrammatic view of a modern downdraft carburetor embodying one form of my invention.

The reference numeral 1 indicates the main body portion of the carburetor having a downwardly directed mixture conduit 2 formed therethrough and having a constant level fuel chamber 3 formed integral therewith. The lower end of member 1 is equipped with a flange 4 for attaching the carburetor to an engine intake manifold. The conduit 2 has a Venturi formed 50 constriction 5 and a pair of concentric Venturi tubes 6 and 7 supported therein. Attached to the top of member 1 is a combination fuel chamber cover and air inlet gasket 8 which has an air inlet 9 formed therethrough. The air inlet

is controlled by a choke valve 10 mounted for rotation on a shaft 11. The outlet of the mixture conduit is controlled by a throttle valve 12 which is mounted for rotation with a throttle valve shaft 13.

A main fuel nozzle 14 is indicated, receiving fuel from float chamber 3 through a metering restriction 15 and passage 16. A conventional idling system is indicated comprising an idling fuel restriction 17, passage 18, 19, 20, air bleed 21, restriction 22, air bleed 23, passages 24 and 25, and discharge port 26. A conventional float 27 acting in a well known manner on an inlet needle valve 28 maintains a substantially constant level of fuel in chamber 3 as indicated by the dot-dash line x—x.

To supply fuel for acceleration, a cylinder 29 in chamber 3 is provided having a reciprocating piston 30 fitted therein. It will be understood that piston 30 may be provided with cup-leathers or any suitable sealing device to prevent leakage thereby. An inlet passage 31, 32 from chamber 3 to the lower part of cylinder 29 is provided. This passage is controlled by an inlet check valve 33. Fuel is discharged from cylinder 29 into the mixing conduit through passages 34, 35, 36 and discharge nozzle 37. A discharge check valve 38 is provided. A check controlled air bleed 39 to passage 36 is provided to prevent pull-over due to suction in the mixture conduit.

Piston 30 carries firmly attached thereto an upper, smaller concentric piston 40 which reciprocates in a cylinder 41 formed in the upper casting 8. The upper end of cylinder 41 communicates with the mixing conduit 2 posterior to the throttle valve through passages 42, 43, and 44. By this arrangement the piston 30 is drawn upward by suction to fill the cylinder 29 with fuel. A spring 45 in the upper part of cylinder 41 which normally urges the piston assembly downward to its discharge stroke is provided. Formed as a part of piston 40 and extending downwardly through the body casting is a plunger rod 46 which engages one end of a rocker arm 47 which is pivoted at 48. The opposite end of rocker arm 47 is acted upon by a cam 49 rigidly attached to the throttle valve shaft 13. By this arrangement, a definite maximum discharge stroke of the accelerating device for a given throttle opening is obtained. Rising upwardly from the bottom of cylinder 29 to a point substantially above fuel level is a tube member 50 which acts as a guide for rod 46 and prevents leakage of fuel. The piston 30 is also provided

with a central perforation which slidably receives the guide member 50.

In operation, when the throttle valve is opened to accelerate the engine there will be a drop in vacuum in the induction system posterior to the throttle, the amount depending upon the load on the engine and the rate and extent of throttle opening. Assuming the engine has the usual motor vehicle load, it is obvious that there will be less drop in vacuum for a given rate of throttle opening if the vehicle is descending an incline than if it were ascending. Under acceleration with light engine loads, less accelerating fuel is required and with the arrangement shown less fuel will be delivered.

On the other hand, it will be appreciated that variable friction and spring rate tolerances are encountered in production and that for slight accelerating discharges, which amounts must be accurate, the definite limitation of the discharge stroke for a given throttle opening, which is provided in this arrangement, permits wider manufacturing tolerances and, therefore, more economical production.

The foregoing description and accompanying drawing are intended to be illustrative and not limiting and the use of all modifications within the scope of the appended claims is contemplated.

I claim:

1. In a carburetor having a vertical mixture conduit, a throttle valve mounted on a transverse rotatable shaft in the lower part of said conduit, a constant level fuel chamber adjacent said conduit and above said throttle, a cover for said fuel chamber, an accelerating well in said fuel chamber, a vertical guide member centrally located in said well and rising from the bottom thereof to a point substantially above the level of fuel, said guide member and the bottom of said well being provided with a continuous vertical bore extending from the exterior below said fuel chamber upward through said guide, a piston in said well arranged to displace fuel from the lower part thereof, said piston having a central perforation adapted to slidably receive said guide, an operating rod extending from the exterior below said fuel chamber upwardly through said guide to a point above said guide and having a downwardly extending portion exterior of said guide member and attached at its lower end to said piston, an eccentric mounted on said throttle shaft, a rocking arm between said eccentric and the lower end of said operating rod, and a spring bearing against said cover and the upper end of said operating rod to urge said piston downward.

2. In a device of the class described, a constant level fuel chamber, an accelerating well in said chamber, a vertical guide member centrally located in said well and rising from the bottom

thereof to a point substantially above the level of fuel, a piston constructed and arranged to displace fuel from the lower end of said well and having a central perforation adapted to slidably receive said guide, said guide member and the bottom of said well being provided with a continuous longitudinal bore therethrough, and an operating rod slidably fitted in said bore and extending from the exterior below said well to a point substantially above the upper end of said guide member and having an integral portion thereof extending downward from its upper end exterior of said guide member and rigidly attached to said piston.

15 3. In a device of the class described, a pair of opposed vertical cylinders, the lower of said cylinders being a pumping cylinder and being arranged to receive and discharge liquid fuel from its head end, the other of said cylinders having a connection from its head end to a source of varying suction, a composite hollow piston having a head at both ends and being arranged to work in said opposing cylinders, a longitudinal guide member centrally located in said lower cylinder being attached to the head thereof and extending beyond the upward travel of the lower end of said piston, the lower head of said piston being centrally perforated to slidably receive said guide, said lower cylinder head and said 20 guide member having a longitudinal bore extending therethrough, a control rod extending from the exterior below said lower cylinder through the bore in said lower cylinder head and said guide member and being attached to the upper head of said piston, and a pump discharging spring in the head end of said upper cylinder.

35 4. In a carburetor having a vertical mixture conduit, a constant level fuel chamber adjacent said conduit, a throttle valve in said conduit below said chamber, an accelerating fuel well in said chamber, a vertical guide member centrally located in said well and rising from the bottom thereof to a point substantially above the level 40 of fuel, said guide member and the bottom of said well being provided with a central continuous bore extending from the upper end of said guide member to the exterior below said fuel chamber, a cup-shaped piston arranged to displace fuel 45 from the lower part of said well, said piston having a central perforation therethrough adapted to slidably receive said guide, an operating rod extending from the exterior below said chamber through said guide and above the upper end thereof, said rod having a portion extending downwardly from its upper end surrounding said guide member and being attached to said piston, and an operating connection between said 50 throttle and the lower end of said rod.
